Primary Examiner — Lauren R Calve(74) *Attorney, Agent, or Firm* — Bold IP, PLLC;
Christopher Mayle(57) **CLAIM**

The ornamental design for a pipe beveling attachment for hand router, as shown and as described.

DESCRIPTION

FIG. 1 is a top perspective view of a pipe beveling attachment for hand router in accordance with the present invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a bottom perspective view thereof; and,

FIG. 9 is an exploded perspective view thereof.

The broken lines shown represent portions of the pipe beveling attachment for hand router that form no part of the claimed design.
